UNITED STATES PATENT OFFICE.

ALBION D. T. LIBBY, OF ELYRIA, OHIO, ASSIGNOR, BY MESNE ASSIGNMENTS, TO THE GARFORD MANUFACTURING COMPANY, OF ELYRIA, OHIO, A CORPORATION OF OHIO.

COMPOSITE ELECTRIC SYSTEM.

1,137,150.

Specification of Letters Patent. Patented Apr. 27, 1915.

Application filed August 28, 1909. Serial No. 515,044.

To all whom it may concern:

Be it known that I, ALBION D. T. LIBBY, a citizen of the United States, residing at Elyria, in the county of Lorain and State of Ohio, have invented certain new and useful Improvements in Composite Electric Systems; and I do hereby declare the following to be a full, clear, and exact description of the invention, such as will enable others skilled in the art to which it appertains to make and use the same.

My invention relates more particularly to combined telephone, police, and fire systems.

I contemplate more particularly a system in which I provide an arrangement for signaling the various stations along the line by means of some kind of attractive signals, located at the sub-stations. I use on the system which I herein disclose, a plurality of lamps which may be operated to burn continuously, or which may be flashed.

Among other purposes of my invention, are:

First. Means for connecting the source of signaling current to the line, and means for automatically disconnecting this source and thereby retiring all the signals when any sub-station upon that line responds.

Second. Means for recording the police signal sent in, and the date thereof. I provide a signal at a special station which may be the barn or the patrolman's station, which signal is not operated by the ordinary police report signaling apparatus but which is operated by circuits controlled through a special means at the sub-station.

Third. I provide a line signal relay at the central station and a line relay which acts to automatically cut off the line signal relay when a police report signal is being sent in. At the sub-station I provide a signal which may be in the police box and which is automatically operated when the glass covering the key receptacle, is broken.

45 I also provide a system in which I combine means for sending a signal from the sub-station to the main station and recording the same there, means for signaling the main station independent thereof, means for telephoning between these stations and means at the substations under control of the main station attendant for signaling an itinerant person in the neighborhood of the sub-station.

55 While I have described my system as be-

ing more particularly intended for a police system, I contemplated its use for other and similar purposes where itinerant persons or where workmen or others who are ordinarily in the vicinity of the boxes are to be signaled.

My invention will be best understood by reference to the following description when taken in connection with the accompanying illustration showing one specific embodiment thereof, while its scope will be more particularly pointed out in the appended claims.

Figure 1 is a diagram of the circuits and apparatus constituting the system. Fig. 2 is a modification of the signal sending apparatus at the central station. Fig. 3 is a perspective of the sub-station box showing the doors open. Fig. 4 is a horizontal cross section of the box showing both doors open. Fig. 5 is a vertical cross section showing the doors closed.

Referring to the drawings and to the embodiment of my invention there shown, I have illustrated in Fig. 1 a central office at I. At II I have illustrated merely diagrammatically a sub-station. At III I have illustrated in detail the circuits and apparatus of a sub-station; and at IV, the fire signal receiving station. At V I show a special station; such as, the patrol wagon barn, or stable. The batteries are illustrated at B, B¹, B², B³, B⁴, B⁵, B⁶, B⁷, and B⁸. I may combine these batteries when I find it practical and convenient, so as to make one battery perform the work of two or more as illustrated. The batteries have been illustrated thus for the sake of convenience in the diagram. A source of signaling current is shown at A. This source is controlled by electromagnets S and S¹. The line signal is shown at S⁸; a buzzer, at F; and the line relay, at S⁵. K is a signal at the central station which indicates the police signals to the central operator. S⁶ is a relay controlling the police signal recording mechanism M. At the termination of the revolution of M, a circuit through the magnet S¹⁵ is completed, and a record of the time of the motor clock O is stamped upon the tape N. A slow acting magnet S⁷ controls the signal relays S⁹ and S¹⁰, S⁹ being placed at the special station V. The magnet S¹⁰ controls the signal P at the central operator's desk. The central operator's telephone set is shown at 110

X. At the sub-station I show a signal controlling relay S^2 and condenser C bridged across the line. The signal lamp is shown at L ; the substation transmitter, at T' ; the telephone hook, at H' ; and the receiver, at R' . The police signal sending apparatus is shown at D . At Q I show a lightning arrester in the fire alarm circuit. At the station IV, I show a relay S^3 which is normally energized and which is adapted to close a circuit through the relay S^4 which operates the fire signal recording apparatus E .

Having thus described the more prominent parts of the apparatus and circuits, I will now describe the details in connection with the operation. The operation of my system is as follows: Should the central operator desire to call the patrolman to the sub-station apparatus, he closes the switch 5 which completes the circuit from ground G through the switch 5, conductor 6, the relay S^1 , battery B^7 , to ground G^2 . The relay S^1 pulls up armatures 7, 8 and 9 which break the connection at 7-10, 9-11, and close the contacts 7-12, 8-13, and 9-14. This completes first, a locking circuit of the relay S^1 , as follows: ground G^1 , switch 15, conductor 16, armature 17, and co-operating contact 18, conductor 19, switch 13-8, S^1 , B^7 to ground G^2 . A circuit through the generator A is completed as follows: $A-S-20-12-7$ -line limb 21, to the sub-stations, at the various sub-stations through the bridges 22, including the condensers C and the signal controlling relays S^2 to the other line limb 23-9-14-back to the generator A . This operates the relays S^2 which pulls up the armatures 24, engaging the contacts 25 which completes a circuit through the lamps L . The lamps L are bridged on the lighting mains 26 and 27. The relays S and S^2 are alternating current relays. As long as the circuit is through the relay S^2 , the energy in the circuit is insufficient to operate the relay S . As soon as any of the subscribers on the system answers the signal by removing the receiver R' from the hook switch, the low resistance talking bridge is completed around the bridge 22 through the transmitter T' to the receiver R' . The current flowing through this bridge is sufficient to operate the relay S which pulls up its armature 17, interrupting the locking circuit of the relay S^1 which is immediately de-energized, permitting its armatures 7, 8, and 9 to fall back, disconnecting the generator A , and completing the line circuit. Both the relays S and S^2 are de-energized, allowing the signaling system to return to normal condition. The switch 15 is provided in order that I may interrupt the locking circuit manually if there is no response to the signals at the sub-station. When the armatures 7 and 9 fall back completing the line limbs, a circuit

is closed through the line signal S^8 as follows: battery $B^1-25-26$ -armature 27 of relay S^6 -contact 28-29-30-31-32-33-11-9-23-sub-station bridge 34-through $T'-R'-21-7-10-35-36-37-38$ -the line signal S^8 , back to Battery B^1 . This energizes signal S^8 which throws the drop 40, completing a circuit through the buzzer F as follows: 40-41-F-42-the closed switch 43-44-25-battery B , back to the drop 40. The buzzer F is operated, indicating to the central operator that the sub-station has responded, or, as the case may be, that the sub-station is calling in. He immediately operates the switch 50, disconnecting the signal receiving apparatus by breaking the contacts 31-32 and 36-37, and closing a circuit through the central talking set by closing the contacts 3-36 and 4-32. This completes the talking circuit between the central and sub-stations as follows: $T-2-4-32-33-11-9-23-34-T'-H'-R'-21-7-10-35-36-3-1-51-R-H$ -back to T . Current is supplied to this circuit from the battery B through the induction coils 52 and 53. These coils serve to choke out the variations in the battery current.

The operation of the police signal sending and recording means is as follows: The sub-station operator pulls down the lever 54 of the signal sending apparatus D which opens and closes the following circuit which is designed to furnish a different signal for each sub-station. These signals are recorded at the central station so that the central operator knows which sub-station signal sending apparatus has been actuated. A circuit is completed from ground G^3 at the sub-station-55-through D -the pins 56-spring 57-58-23-9-11-33-32-31-30-the line relay S^5 -60-battery B^4 to ground G^9 . This energizes the relay S^5 according to the code signal of the particular sub-station apparatus. Relay S^5 pulls up its armatures 27 and 61, interrupting the connection of the line signal S^8 to the line, and preventing its operation during the sending of the impulses. The armature 61 engages contact 62, completing a circuit through the bell K and the relay S^6 , as follows: battery $B^4-63-64-S^6-65-K$ -the switch 66-67-62-61-60-back to battery B^4 . This energizes the bell K and the relay S^6 . S^6 pulls up its armature 70 permitting the operation of the spring motor and signal recording apparatus M . The signal is then recorded upon the tape N , and at the end of the rotation of the motor M , the lug 71 engages a spring 72 closing the switch 72-73. This completes a circuit through the magnet S^{15} as follows: $S^{15}-74-75$ -battery $B^4-63-64-72-73-78$ -back to magnet S^{15} . The magnet S^{15} pulls down its armatures 79 and 80, stamping upon the ribbon the time registered by the motor clock 130

5 through the circuit of B^3 and the stamp Z. When the relay S^6 is energized, it closes a switch 81-82 which completes a circuit through the relay S^7 as follows: S^7 -83-
 10 75-battery B^4 -63-84-81-82-85-back to relay S^7 . A condenser C^1 is bridged across the contacts 81-82. The energization of the relay S^6 by the code signal sending apparatus is not of sufficient duration to 15 close the contacts 81 and 82 long enough to energize the slow acting relay S^7 sufficiently for it to pull up its armature. Should the sub-station operator desire to call for a patrol wagon, the button 91 is pressed down 20 to close the switch 90-92, and held there for a short space of time. This completes the circuit from ground G^3 -90-92-58-23-
 25 9-11-33-32-31-30-line relay S^8 -60-
 B^4 -to ground at G^9 . The relay S^8 is energized, closing a circuit, as above described, through relay S^9 which closes a circuit previously described, through relay S^7 . The key 91 is held down long enough to energize the slow acting relay S^7 which pulls up the 30 armature 94 to engage the contact 95, completing a circuit through the signal relays S^9 and S^{10} , as follows: ground at G^9 - B^4 -
 35 75-83-94-95-96-and through the relay S^9 to ground G^{10} and S^{10} to ground G^{11} in parallel. The drops of these two relays are thrown, and a circuit completed through the signal P. The drop V is located at the wagon barn, and its operation indicates that a wagon is desired. This enables the driver 40 to prepare to depart in advance of the order directly from the chief patrolman located at the central office.

At S^6 I illustrate the line relay of a second line (not shown but similar to the line 45 21-23). This relay is connected by 60' to the battery B^4 and by 30' to its line. It controls an armature 61' adapted to engage the contact 62' which is connected through the switch 66' to the signal bell K, and a second armature 27' which normally engages the contact 28' connected to the lead 30'. When a line relay is energized, the interruption of the connection at 27-28 serves to prevent current from passing from B^4 50 through the contacts 60-60'- S^5 -29'-
 55 28'-27'-26'-27-28-29 to 30 and ground through D, energizing the relay S^7 and giving a false signal on that line.

The fire alarm system operates as follows: 60 I use the same signal sending apparatus at the substation, but a different signal receiving apparatus which is here shown at the station IV, but may be located at the same station as the other central station apparatus. In the fire alarm system, the apparatus D is normally shunted through the shunt 100, 101, 102 and 103. A key to the box is placed in a receptacle 105 which is inclosed by a glass or other suitable plate 65 104. The glass is broken, and immediately

upon the breaking thereof, the lug 108 is relieved. The normally closed switch 101-102 is interrupted, breaking the shunt of the apparatus D and closing a switch 106-107. This switch closes a circuit through the lamp 70 L as follows: L-110-106-107-111-27 to the source of lighting current 26, back to the lamp L. The fire alarm signal receiving apparatus at the station IV is now operated over the following circuit: from ground at 75 G^6 -112-113-114-115-116-117- S^2 -battery B^6 -to ground at G^6 . The armature 120 alternately engages and disengages contact 121, completing and breaking a circuit through the relay S^4 . This circuit 80 is as follows: ground at G^6 -battery B^6 -120-121- S^4 - G^7 . The signal is recorded on the tape of the apparatus E.

In the modified form in Fig. 2 I have dispensed with the feature whereby the substation signaling current is automatically disconnected. I show a key switch 125 which controls the contacts 126-127, and, when operated, completes a bridge on the line through the battery B^2 . This serves to operate the signal controlling means at the sub-stations.

In Figs. 3, 4, and 5 I show the box at the police station. At 105 is shown a receptacle for the key to the box which is inclosed by 95 a glass plate and which may be reached by breaking the glass. The switch button 108 is also shown on this box, and is normally prevented from operation by engaging the glass plate. When the glass is broken, this 100 switch button is released, operating to change the circuit as previously described.

The interior of the box is divided into two compartments. The interior compartment is closed by the door 150 which bears upon 105 its back the apparatus D and upon its front, a telephone transmitter and receiver. The hook switch is pivoted to the rear of the door 150 within the compartment where the contacts completed thereby are located. The 110 lever 54 is also pivoted to the rear of the door and projects therethrough, being accessible from the exterior of the inner compartment. The inner door 150 is pivoted intermediate its ends at 151 and 152. By 115 pivoting this door intermediate its ends, I am enabled to swing it out so as to be able to approach the apparatus upon the rear thereof without removing any of the apparatus which projects through the front 120 thereof, and without damaging or interfering with the same. This will be readily understood from Fig. 4 of the drawing which shows the inner door open. The outer door 153 is hinged to the outer edge of the box 125 and serves to close the exterior compartment as well as the box itself. On the interior of the exterior door at the top and along both sides I show a ridge 154 which cooperates with a gutter 155 cut in the box. At the bot. 130

tom of the door I show a lip 156 which cooperates with a part 157 on the box. This arrangement is provided to make the box water-proof. Any water running down over the ridge 160 will be caught by the gutter and carried down and discharged at the bottom of the box. Water running down the surface of the door will be carried clear of the box by the lip 156. Upon the back 10 of the box I show a lamp signal L. In the sides of the box recesses are cut and lenses 162, 163 and 164 inserted therein. Through these the light rays from the lamp pass to the exterior of the box. In the inner door 15 there is provided a recess 161 which cooperates with the recess of the lens 164 in the outer door 153 so that the light rays pass straight through the two doors to the exterior thereof, or the lamp itself may project 20 from the inner compartment through the recess 161.

While I have shown this particular arrangement of circuits and apparatus, it will be obvious to those skilled in the art, that 25 numerous and extensive departures from the form and details of the apparatus and circuits here shown, may be made without departing from the spirit of this invention, the same being herein shown solely for the 30 purpose of clearly illustrating one specific embodiment thereof.

I claim:

1. In a composite electric system, the combination of a telephone circuit, a fire alarm circuit, a motor operated signal sending device in said circuit, a central station, sub-stations in said telephone circuit, a lamp signal at each substation and means at each substation adapted to cause the actuation 40 of the signal at said substation and to control said fire alarm circuit at said substation.

2. In a composite electric system, the combination of a telephone circuit, a fire alarm circuit, a central station, sub-stations 45 in said telephone circuit, a visible signal at each substation and means at each substation controlling the signal at said substation and the fire alarm circuit connected to said substation whereby said signal and said fire alarm circuit may be actuated simultaneously.

3. In a composite electric system, the combination of a telephone circuit, a fire alarm circuit, a central and sub-stations in 55 said telephone circuit, lamps at said sub-stations, a circuit for said lamps and means at each substation controlling the lamp thereat and the fire alarm circuit connected to such substation, said means being connected 60 mon to said lamp and said fire alarm circuit.

4. In a composite electric system, a telephone circuit, a fire alarm circuit, a central and sub-stations in said circuit, motor operated fire alarm signal sending apparatus 65 at each substation, a lamp signal at each

substation and switching means common to said signal sending apparatus and said signal at said substation controlling both the signal sending apparatus and the signal at said substation.

5. In a composite electric system, the combination of a police and fire system, a central and sub-stations in said system, normally closed police boxes at said sub-stations, opening means for said boxes, an inclosure for 70 the opening means, signals in said boxes, signal sending apparatus in said boxes, and means operated automatically by the breaking of the inclosure, controlling both the signals and the signal sending apparatus. 80

6. In a composite electric system, the combination of a police and fire system, a central and sub-stations in said system, normally locked police boxes at said sub-stations, unlocking means for said boxes, an 85 inclosure for said unlocking means, a glass front for said inclosure, signals at said sub-stations, signal sending apparatus at said sub-stations, a switch acting automatically when the glass front is broken to actuate 90 said signal and to control said signal sending apparatus.

7. In a composite electric system, the combination of a central station, signal recording means at said central station, a signal 95 adjacent to said central station, a slow acting relay controlling said signal, sub-stations on said system, current impulse sending means at the sub-stations adapted to produce impulses to operate the signal recording means at the central station, a circuit for said slow acting relay, a relay controlling said slow acting relay circuit, said slow acting relay being irresponsive to said impulses and means at the sub-stations to 100 close a circuit through said controlling relay to actuate said slow acting relay whereby said adjacent signal is operated.

8. In a composite electric system, the combination of a central station, signal recording means at said central station, a signal 110 adjacent to said central station, conductors connecting said signal and said central station, a slow acting relay controlling said signal, a circuit for said slow acting relay, a relay controlling said slow acting relay circuit, and said signal recording means, a plurality of sub-stations, conductors connecting said sub-stations, and said main station, current impulse sending means at the 120 sub-stations adapted to produce impulses to operate the signal recording means at the central station, said slow acting relay being irresponsive to said impulses, and means at the sub-stations to close a circuit through 125 said slow acting relay to actuate the same to operate said adjacent signal.

9. In a composite electric system, a combined telephone and police system, a central station and a sub-station on said system, a 130

signal adjacent to said central station, signal sending means at said sub-station, signal recording means at said central station adapted to be operated by impulses of current originated by said signal sending means, a slow acting relay in said system in circuit with said signal sending means, but irresponsible to the impulses originated thereby, and means at the sub-station for closing a circuit normally open at said means whereby said slow acting relay is actuated to close a circuit through said adjacent signal.

10. In a composite electric system, the combination of a central station, signal recording means at said central station, a signal adjacent to said central station, a slow acting relay controlling said signal, a sub-station on said system, current impulse sending means at the sub-station adapted to produce impulses to operate the signal recording means at the central station, said slow acting relay irresponsible to said impulses, and means at the sub-station to close a circuit normally open at said means through said slow acting relay to actuate the same to operate said adjacent signal.

11. In a composite electric system, the combination of a combined police and telephone system, a central station and a sub-station on said system, a line signal at said central station, means in said system controlling said signal, police signal sending means at said substation and means actuated when the police signal sending means is operated to positively interrupt the connection of said line signal controlling means with the system.

12. In a composite electric system, the combination of a central station and a sub-station on said system, a station adjacent to said central station, signaling apparatus at each of said stations, a relay at the central station controlling said adjacent station signaling apparatus, circuit making and breaking impulse sending apparatus at the sub-station adapted to actuate said signaling apparatus at the central station, said relay being irresponsible to the impulses of said impulse sending apparatus, and a normally open switch at said sub-station for operating said relay whereby the adjacent station signaling apparatus is actuated.

13. In a composite electric system, the combination of a telephone, a fire and a police system, police signal receiving means, fire signal receiving means, a sub-station on said system, a circuit from said substations to said police signal receiving means, a second circuit from said sub-station to said fire signal receiving means, signal sending means at said sub-station common to both said signal receiving means, a shunt in said fire circuit around said signal sending means rendering said fire signal

recording means normally irresponsible thereto.

14. In a composite electric system, the combination of a police, a fire, and a telephone system, police signal receiving means 70 in said system, a sub-station in said system, circuit making and breaking signal sending means at said sub-station adapted to operate said police signal receiving means, a fire station in said system remote from said central station, fire signal receiving means at said fire station, a circuit connecting said substation and said police signal receiving means, and a second circuit connecting said substation and said fire signal receiving 80 means, a shunt in circuit of said signal sending means rendering said fire signal receiving means normally irresponsible thereto, and means for interrupting said shunt.

15. In a composite electric system, the combination of a police, a telephone and a fire system, police signal receiving means, a substation in said system, signal receiving means, a circuit connecting said substation and said police signal receiving means and 90 a second circuit connecting said substation and said fire signal receiving means, common means at said station for operating the signal receiving means, means at said sub-station rendering the fire signal receiving 95 means normally irresponsible to the sub-station signal operating means, and a device at the sub-station within an inclosure, said device adapted to be automatically operated when said inclosure is broken to render said 100 fire signal receiving means responsive to said sub-station signal operating means.

16. In a composite electric system, the combination of a telephone, a fire and a police system, police signal receiving means, 105 fire signal receiving means, a substation on said system, a circuit connecting said sub-station and said police receiving means and a second circuit connecting said substation and said fire signal receiving means, signal 110 sending means common to said signal receiving means at said sub-station, circuits connecting said signal sending and said signal receiving means, a shunt in the circuit of the fire signal receiving means around said 115 signal sending means rendering the same normally inoperative thereto, a device at the sub-station within an inclosure controlling said shunt and adapted on interruption of the inclosure to automatically open said 120 shunt to render the fire signal receiving means responsive to the signal sending means.

17. In a composite electric system, the combination in a police and fire system, a 125 central and sub-stations in said system, normally closed police boxes at said substations, fastening means for said boxes, means for controlling said fastening means, an inclosure for the controlling means, signals in 130

said boxes, signal sending apparatus in said boxes, and means operated automatically by the breaking of the inclosure controlling both signals and the signal sending apparatus.

18. In a composite electric system, the combination in a police and fire system, a central and substations in said system, normally closed police boxes at said substations, fastening means for said boxes, means for controlling said fastening means, an inclosure for the controlling means, lamp signals

in said boxes, signal sending apparatus in said boxes, and means operated automatically by the breaking of the inclosure controlling both signals and the signal sending apparatus. ¹⁵

In testimony whereof I affix my signature in presence of two witnesses.

ALBION D. T. LIBBY.
